US0D1057693S

(12) **United States Design Patent** (10) **Patent No.:** **US D1,057,693 S**
Shu (45) **Date of Patent:** **** Jan. 14, 2025**

(54) **SHARK FIN ANTENNA**

(71) Applicant: **Shenzhen Zhongwei Hanxin Technology Development Co., Ltd., Shenzhen (CN)**

(72) Inventor: **Jun Shu, Shenzhen (CN)**

(73) Assignee: **Shenzhen Zhongwei Hanxin Technology Development Co., Ltd., Shenzhen (CN)**

(**) Term: **15 Years**

(21) Appl. No.: **29/874,449**

(22) Filed: **Apr. 19, 2023**

(51) LOC (15) Cl. **14-03**

(52) U.S. Cl.

USPC **D14/230**

CLAIM

The ornamental design for a shark fin antenna, as shown and described.

DESCRIPTION

FIG. 1 is a front perspective view of a shark fin antenna, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate portions of the shark fin antenna that form no part of the claimed design.

1 Claim, 8 Drawing Sheets
